UNITED STATES PATENT OFFICE.

WALTER H. PAULSON, OF CHICAGO, ILLINOIS, ASSIGNOR TO HARRY D. LATHROP, OF CHICAGO, ILLINOIS.

BOTTLE-WASHING MACHINE.

Application filed January 26, 1927. Serial No. 163,669.

This invention relates to improvements in receptacle washing apparatus, and more particularly to means for anchoring receptacles to the carriers of such washing machines.

The primary object in view is the easily releasable, effective, and simple anchorage of a bottle or like receptacle within its pocket or chalice, affixed to the carrier of 10 the washing apparatus for insuring retention of the receptacle in the proper alignment and condition for being effectively subjected to cleansing actions.

With this and further objects in view, as 15 will in part hereinafter become apparent and in part be stated, the invention comprises retaining devices so coordinated with the pockets or other holders of receptacle washing machines as to enable locking of 20 the receptacles therein by the act of assembling them in the machine, and unlocking the receptacles by the act of removing them from the machine, while insuring effective retention during the progress through the 25 machine.

The invention is especially well adapted for use in conjunction with the type of washing apparatus disclosed in the joint application of Harry D. Lathrop and me, 30 filed July 31, 1925, Serial 47,194.

The invention comprises certain other novel constructions, combinations, and arrangements of parts, as will be hereinafter specified and subsequently pointed out in 35 the appended claims.

In the accompanying drawing:

Fig. 1 is a transverse, vertical section through the charging and discharging end 40 of a washing machine, with embodiments of the invention applied thereto;

Fig. 2 is a transverse, vertical section through the carrier and a receptacle pocket incorporating an embodiment of the invention, parts being seen in elevation, and the 45 parts being shown on a large scale;

Fig. 3 is a fragmentary top plan view of the parts seen in Fig. 2.

In bottle washing machines of the general type to which the present invention is particularly applicable, it has been heretofore proposed to retain the bottles being washed in their proper relation to the carrier of the machine by various forms of more or less crude and expensive apparatus. A well known expediency to this end is included in

the employment of a rod or rods extending along and substantially midway above the path of the receptacles, and sufficiently adjacent the plane of travel of the upper extremities of the receptacles to preclude longitudinal displacements of the receptacles from their pockets. Difficulty has been experienced with such arrangements, however, to successfully confine the receptacles without excessive friction, and even in the most successful embodiments employing restraining rods, objectionable lateral play of the receptacles frequently occurs and results in lack of effective alignment of the receptacles with respect to the path of the cleansing jets. Where substantially high pressure is employed for the fluid of the jets, say 35 pounds, which has been found a very satisfactory pressure, receptacles in such known apparatus have been lifted by the pressure of the jets out of their pockets after playing laterally to one side or the other of the restraining rod or rods.

It is a primary object of the present invention to overcome all these difficulties and to gain other substantial and valuable advantages as will subsequently become apparent.

Referring to the drawing by numerals, 1 indicates the usual endless belt or carrier for the receptacles to be washed. As shown, the belt 1 comprises a chain, but may consist of any suitable substitute. Anti-friction rollers 2 sustain the belt 1 on the horizontal flange of a angle bar track 3. Paralleling the track 3 throughout the parts of the washing machine in which the cleansing operations occur, as in the machine shown in the above identified co-pending application, is a track 4 of similar angle material, arranged to face the track 3 and located relative thereto in a manner to receive and sustain the anti-friction rollers 5, supporting the pockets or receptacle containers 6, each of which pockets is pivotally connected to the belt 1. Each pocket 6 is a duplicate of all others, and is susceptible, of course, of a wide range of modification in detailed construction according to the particular receptacle to be treated. Each pocket 6, however, preferably consists of an open work framing including longitudinally disposed bars 6", and circumferential, integral rings connecting said bars. Bottom plates 6' form a part of pocket 6, and are disposed to 100 105 110 115

directly support the presented terminus of the receptacle to be cleansed. The structure thus far described is substantially the same as disclosed in the above identified application.

For the purpose of providing the pivoted anchorage of pocket 6 to carrier 1, a bracket plate 7 is bolted or otherwise effectively anchored to the angle plates 8, 8, outstanding form and preferably formed integral with parts of the carrier 1. The edge portions of the plate 7 are turned to outstand laterally from the carrier or belt 1, producing the flanges 9, 9, spaced apart and adapted to receive therebetween a web 10, which projects laterally from the respective pocket 6. Webs 10 may comprise various forms, but preferably each consists of a pair of parallel plates, spaced apart at 12, as seen in Fig. 3, sufficiently to cause the webs to be effectively guided by flanges 9 while free to swing therebetween. Webs 10 are pivoted at their lower portion to the lower portion of the flanges 9 in any desirable and effective manner, as by employment of a through bolt 11. Bolt 11 is preferably surrounded by a bushing 13, but of course the pivotal anchorage may be constructed otherwise, as may be desired. The plate 7 terminates somewhat short of the length of the flanges 9 at the lower end, and thus leaves an open notch 7', so located as to accommodate the swing of pocket 6 to the lower position, after the manner indicated in full lines in Fig. 1. By preference, the edge of each web 10 exposed toward the inner face of plate 7 is dimensioned and shaped to fit against said plate when the pocket 6 is held in the upright position by the roller 5 traveling on a horizontal portion of track 4.

Each of the flanges 9 is formed with an edgewise extension 17 terminating in a nose 18, projecting through the open side of pocket 6 into position for snugly engaging the particular receptacle 19 located in the pocket 6 when said pocket is in an upright position, as seen in Fig. 2. The nose 18 in each instance will, of course, be provided with that contour most effective in cooperating with the particular receptacles to be washed. For instance, when milk bottles are being washed, the nose 18 will be rounded and proportioned to engage the side of the neck of the bottle and to overlie and engage the bead 16 present at the terminus of such neck. The bottles are mounted in an inverted position. The bar 6" of pocket 6 diametrically opposite extension 17 is slightly different from all of the other bars of the pocket it being flat or slightly concave to facilitate loading or unloading of the bottles, while the upper portions of all the other bars, as best seen in Fig. 2, are thickened longitudinally to extend inside of the inner circumference of the upper ring of

pocket 6, so as to snugly engage the walls of the bottle 19 when in place in the pocket. The said flat bar 6" opposite nose 18 is preferably provided with an inwardly extending lug 15, adapted to cooperate with nose 18, especially relative to bottles or other receptacles of slightly reduced proportions but otherwise similar to those of the average conventional bottle. The difference in shape of the bar 6" having a lug 15 from the other bars causes a certain amount of clearance to appear at the right hand side of pocket 6 in Fig. 2 between the pocket and the bottle, whereas in fact, the bottle is in snug contact with all of the other bars 6".

So far as the present invention is concerned, it is wholly immaterial what means may be employed for causing relative movement of the pocket 6 with respect to the carrier belt, it being only necessary that the pocket be permitted to swing to an appropriate, inclined position, such, for example, as either of the inclined positions shown in full lines in Fig. 1, or any other location whereat the nose 18 is no longer in the path of the bead of receptacle 19, to enable said receptacle to be placed in or removed from the pocket. In practicing the invention as applied to the washing machine disclosed in the above identified co-pending application, the track 4 is formed with movable sections 4', 4", pivotally sustained and adapted to be actuated by links and power levers 14, 14. Said links and levers 14 function to lower sections 4' and 4" to positions with the pockets 6 swung downward on their pivots 11 to places where the nose 18 in each instance is no longer in the path of movement of the bead of bottle 19. When in either of these positions, the bottle is free to be inserted or removed to or from pocket 6. When inserted, as seen at the right hand side of Fig. 1, and the track section 4" raised to alignment with the main portion of track 4, such movement causes the pocket 6 to move across the extensions 17 so that the noses 18 thereof assume the relation to the bottle 19 seen in Fig. 2, and the bottle is thereby effectively and substantially rigidly anchored in pocket 6 both against lateral play and against possible vertical displacement.

It will be apparent that in operation the bottle 19 will be firmly held in place throughout the traveling of the carrier 1 until the pocket 6 is again free to swing laterally relative to the carrier. When this occurs, as seen at the left hand side of Fig. 1, the pocket 6 moves away from the detent comprised of the noses 18 and thereby releases the bottle 19 for easy withdrawal. Thus it will be observed that the locking apparatus is effective while locking of the receptacle is required, and, at the same time, it does not interfere with the charging and

discharging of receptacles in the regular operation of the machine. Furthermore, no especial provision must be made for manipulation of moving parts in order to effect 5 either the locking or the releasing of the receptacles relative to the pocket 6.

What is claimed is:

1. The combination, with the carrier of a receptacle washing machine, of a receptacle pocket pivoted to the carrier to swing to and from an operative relation with the carrier for loading and unloading receptacles to and from the pocket, and means outstanding from the carrier to engage the 15 receptacle in the pocket when in operative position for locking the receptacle in the pocket.

2. The combination, with the carrier of a receptacle washing machine, of a receptacle pocket pivoted to the carrier to swing to and from an operative relation with the carrier for loading and unloading receptacles to and from the pocket, and a projection outstanding from the carrier in position to overhang a part of the receptacle while the latter is in the pocket when in operative position for locking the receptacle in the pocket.

3. The combination, with the carrier of a receptacle washing machine, of a receptacle pocket pivoted to the carrier to swing to and from an operative relation with the carrier for loading and unloading receptacles to and from the pocket, and a rigid 35 projection fixed to and outstanding from the carrier to overhang a part of the receptacle in the pocket when in an operative position for locking the receptacle in the pocket.

4. The combination, with a carrier of a receptacle washing machine, of a receptacle pocket pivoted to the carrier to swing to and from an operative position, and a projection outstanding from the carrier and located to overhang a part of the receptacle adjacent the base of the pocket when the pocket is in an operative position for locking the receptacle in the pocket.

5. The combination, with the carrier of a receptacle washing machine, of a receptacle pocket pivoted to the carrier and having a lateral opening, and a projection extending from the carrier in position to extend through the opening of the pocket and lie within the pocket to overhang a part of a receptacle in said pocket when the pocket is in operative position.

6. The combination, with a carrier of a receptacle washing machine, of a bracket fixed to said carrier and having an outstanding projection, a receptacle pocket pivoted to said bracket in position to have said projection overhang a part of a receptacle

in said pocket, the pocket being proportioned to swing upon its pivot to a point 65 withdrawing the contained receptacle from being overhung by said projection.

7. The combination, with the carrier of a bottle washing machine, of a bottle pocket having a lateral web and being formed with 70 an opening adjacent the web, means pivoting the web to the carrier, and a projection outstanding from the carrier sufficiently to extend into the lateral opening in the pocket when the pocket is in an operative 75 position relative to the carrier.

8. The combination, with the carrier of a receptacle washing machine, of a receptacle pocket pivoted to the carrier at one side, a projection extending from the carrier in position to overhang a part of a receptacle in said pocket while in operative position, the pocket being adapted to swing from the said operative position to a position releasing the part from the overhang, 85 and a projection extending from the wall of the pocket inward and substantially opposite the first mentioned projection.

9. The combination, with the carrier of a receptacle washing machine, of a receptacle pocket pivoted to the carrier, and means outstanding from the carrier for clamping a receptacle in place within the pocket while the pocket is in operative position without interfering with the pivoting of 95 the pocket away from such position.

10. The combination, with the carrier of a receptacle washing machine, of a receptacle pocket pivoted to the carrier, and a rigid projection fixed to the carrier and 100 outstanding to overhang a portion of a receptacle carried by said pocket when the pocket is in operative position, the pocket being free to pivot to a location releasing the carried receptacle from the overhang.

11. The combination, with the carrier of a receptacle washing machine, of a receptacle pocket carried thereby and movable relative thereto, and means for releasably locking a receptacle in said pocket disposed 110 to be rendered effective and ineffective by the relative location of the pocket with respect to the carrier.

12. The combination, with the carrier of a receptacle washing machine, of a receptacle pocket carried thereby and movable relative thereto, and means fixed relative to the carrier for releasably locking a receptacle in said pocket disposed to be rendered effective and ineffective by the relative location of the pocket with respect to the carrier.

In testimony whereof I have signed my name to this specification.

WALTER H. PAULSON.
